UNITED STATES PATENT OFFICE.

JAMES J. WOOD, OF FORT WAYNE, INDIANA.

ELECTRIC-ARC LAMP.

SPECIFICATION forming part of Letters Patent No. 678,607, dated July 16, 1901.

Application filed December 14, 1899. Serial No. 39,888. (No model.)

To all whom it may concern:

Be it known that I, JAMES J. WOOD, a citizen of the United States, residing at Fort Wayne, in the county of Allen and State of Indiana, have invented certain new and useful Improvements in Electric-Arc Lamps, of which the following is a specification.

This invention introduces certain improvements in electric-arc lamps.

10 These improvements are in part applicable to lamps designed to be fed by alternating currents. They are in part applicable to lamps of the class known as "carbon-feed" lamps wherein the upper carbon is engaged 15 directly with the feeding device, and they are in part applicable to inclosed-arc lamps.

One feature of my invention which is especially applicable to alternating-current lamps is designed to effect a proper and gradual 20 drawing of the arc without the objectionable dancing of the movable carbon that is liable to occur with lamps of this class. To this end I connect the armature or movable member of the electromagnet with the separating 25 device for drawing the arc through the medium of a yielding member, as a spring, which is adapted to yield during the arc-drawing movement, and thereby permit the armature to be attracted suddenly without imparting 30 such sudden movement to the separating device, the latter being restrained in its action by the usual retarder or dash-pot, the said yielding member reacting against a relatively-unyielding member, which also forms part of 35 the connection between said armature and separating device, so that said unyielding member limits the movement communicated through said yielding member or spring and upon the retraction of the armature transmits 40 a movement in the contrary direction.

In the preferred and most simple form of lamp embodying my invention wherein a single magnet is employed to control both the separating and feeding movements, the separating 45 device becomes a feeding device, and the relatively-unyielding member serves to transmit the feeding movements from the armature to said feeding device. The relatively-unyielding member constitutes a lost- 50 motion device or movable stop acting in opposition to the yielding member or spring, so as to receive the reaction thereof and to pro-

vide a means by which the yielding member may be given an initial stress, so that upon the attraction of the armature the stress which 55 is transmitted to the separating device is in excess of such initial stress. Thus my invention enables the pressure by which the separating movement is effected against the retardation of the dash-pot to be augmented 60 so as to attain an initial pressure adequate for insuring a firm and progressive movement and to avoid the objectionable dancing effect heretofore experienced.

My invention also provides a convenient 65 means for adjusting the lamp for greater or less current by varying the leverage with which the spring or yielding member acts to transmit its stress to the feeding device, and this without altering the initial stress of such 70 spring. This I accomplish by causing the spring to act against one arm of a lever, which arm is made extensible by means of a nut or sleeve against which the spring acts and which screws upon the threaded portion 75 on the lever so as to move toward or from the fulcrum of the lever the point of application of the stress of the spring.

Those improvements which relate to the carbon-feed lamp involve means for making 80 electrical connection between the trolley and its tube without danger of pitting the tube and provide an improved clutch by which the trolley grasps the carbon, means for properly centering the trolley when introducing the 85 carbon, and an improved clutch for engaging and feeding the carbon.

Those improvements which are applicable to an inclosed-arc lamp include an improved globe-holder for the arc-inclosing globe and 90 an improved construction of gas-cap for closing the top of said globe.

The several improvements provided by my present invention are especially designed for conjoint use in an inclosed-arc carbon-feed 95 lamp to be employed with alternating currents. The preferred construction of such lamp is shown in the accompanying drawings, wherein—

Figure 1 is a vertical mid-section of the entire lamp. Fig. 2 is a fragmentary vertical mid-section on a larger scale than Fig. 1, and in a plane at right angles to that of Fig. 1, the planes of Figs. 1 and 2 being denoted, re-

spectively, by the line 1 1 and the line 2 2 in Fig. 3. Fig. 3 is a transverse section on the line 3 3 in Fig. 2. Fig. 4 is a transverse section of the gas-cap, taken on the same plane 5 as Fig. 1 and showing its parts slightly separated. Fig. 5 is a plan, and Fig. 6 a transverse section, of the feeding-clutch. Fig. 7 is a plan of the globe-holder, of which Fig. 8 is a side elevation and Fig. 9 a fragmentary 10 vertical section, the latter being an enlarged fragment of Fig. 2. Fig. 10 is an elevation of one of the springs shown in Figs. 7, 8, and 9. Fig. 11 is a vertical mid-section of the trolley-tube, trolley, and upper carbon. Fig. 15 12 is an elevation of the trolley removed, of which Fig. 13 is a vertical mid-section. Fig. 14 is a cross-section on the line 14 14 in Fig. 12, and Fig. 15 is a plan or end view of the trolley. Fig. 16 is a fragmentary view of the 20 intermediate or dash-pot lever of the feed mechanism, showing the adjustable spring connection. Fig. 17 includes a side and edge view of the link which constitutes the unyielding member of the connection between the armature and feeding device.

In some respects the construction of lamp shown in the drawings resembles that set forth in my Patent No. 638,789, dated December 12, 1899.

30 Referring to the drawings, let A designate the mechanism-case; B, the frame supporting the mechanism; C, the usual main or outer globe; E E, the usual side rods, which, as shown, extend down within the globe and 35 carry the lower-carbon holder, and M a regulating or control magnet or solenoid, the movable member or armature *m* of which is connected to an armature-lever F, which is pivoted at *a*. The armature is shown as a 40 U-shaped laminated solenoid-core and is connected to the armature-lever F by springs *s s*, Fig. 3, in the manner fully set forth in my Patent No. 638,789.

H is the clutch or clutch-lever, which in a 45 lamp having a feed-rod would engage such rod, but in the particular construction of lamp shown engages the upper carbon I. The lower carbon J is shown as held in the lower-carbon holder K, which may be of any 50 suitable construction, the particular construction here shown being that which is set forth and claimed in my Patent No. 662,048, of November 20, 1900. The upper carbon I is held at its upper end in a spring-holder L, 55 formed at the lower end of a so-called "trolley" N, Figs. 11 to 15, which slides freely in a trolley-tube D, which is fixed in place in the lamp, as shown in Figs. 1 and 2.

I will now describe the means for operating 60 the clutch H from the armature *m* of the control-magnet. In the construction shown the armature-lever F communicates the movements of the armature to an intermediate lever P, which is conveniently placed above it and which in turn connects through a link Q with one arm of the clutch-lever H, the opposite arm thereof being shown as forked and

engaging an adjustable stop-screw *b*. A retarder R, of which a dash-pot is the best example, is connected in any suitable manner 70 to the clutch H, so as to retard the separating or arc-drawing movement thereof. A convenient way of making this connection is by jointing the dash-pot directly to an arm, forming a prolongation of the lever P, as 75 shown. The dash-pot has a check-valve *c*, which opens outwardly, so that it closes during the arc-drawing movement, and thereby acts to retard this movement, while during the feeding movement it opens, and consequently effects no retardation of the feed, this being a known expedient in lamps of this type. The lever P is fulcrumed at *d* to any suitable part, a pendent or bracket *d'* being shown for this purpose projecting down from 80 the top plate *e* of the mechanism-frame B. The relatively yielding and unyielding members heretofore referred to are preferably interposed between the levers F and P and are shown as being respectively a spring S 85 and link T. The spring S is shown as connected with the levers to the left of the fulcrums *a* and *d* in Fig. 2, while the link T is shown as connected to the right of these fulcrums, so that these two members act in 90 opposition to each other. The link T is shown as pivotally connected at its lower end to the lever F by engaging a hole *f* therein, while at its upper end it has a lost-motion connection with the lever P, formed as a slot *p* in this lever, in which the upper end of the link engages. The link is preferably formed as a 95 bent wire, as shown in Fig. 17, its lower part *t* engaging the hole in the lever F and its upper part *t'* engaging the slot in the lever P. 100 Normally the tension of the spring S pulls down the short arm of the lever P and keeps its long arm pulled up, so that the link T is kept seated at the bottom of the notch *p*, so that the lost motion is kept taken up, and 105 the abutting surfaces of the link are slit, constituting spaces for limiting the contraction of the spring. Thus the spring may be stretched to any initial stress desired, the relatively-unyielding member T serving to receive the 110 normal or initial reaction of the spring.

Upon turning on the current the magnet M is instantly energized and attracts its armature *m* with great force, thereby drawing it up and tilting the lever F to the position shown in dotted lines in Fig. 2. This communicates an upward movement through the link T, which slides its upper end *t'* upwardly through the slot *t* to approximately the position shown in Fig. 16. The same movement 115 pulls down the lower end of the spring S, thereby increasing the tension or stress upon this spring. The lever P is now exposed to the unbalanced stress of the spring S, tending to throw it up to the position indicated in 120 dotted lines in Fig. 2; but this tendency is resisted by the retarder R, so that the movement of the lever P occurs very slowly in response to the sudden movement of the lever 125

F. As the lever P slowly moves up under the moderating influence of the retarder or dash-pot it pulls up through the link Q upon the clutch H, causing the latter to engage the upper carbon I and lifting the tail of the clutch free from the stop-screw b until it is elevated approximately to the position indicated in dotted lines, its movement being arrested by the bottom of the notch p encountering the upper bend t' of the link T, whereby the lever P is stopped in the position shown in dotted lines in Fig. 2. It will be perceived that this portion t' of the link T constitutes, in effect, a movable stop, deriving its movements from the armature and acting in one direction as a more or less positive limit to the movement induced under the stress of the yielding member or spring S. In the upward movement of the clutch H it carries the carbon I with it, and thereby draws the arc. In this operation the clutch H constitutes a carbon-separating or arc-drawing device. Subsequently as the carbon consumes and the arc burns long the magnet M becomes weakened, relaxing its attraction for its armature, which accordingly descends, and in this movement the lever F pulls downwardly through the link T upon the lever P, so that the long arm of the latter is moved downward, thereby through the link Q lowering the clutch H and the carbon I to shorten the arc. This movement is not retarded by the dash-pot R by reason of the opening of the valve c, so that the feed occurs promptly. When this feeding movement has continued far enough to disengage the clutch so that the carbon I feeds down through it, the consequent shortening of the arc reenergizes the magnet M, which reattracts its armature, thereby again communicating an upward movement through the link T, which again slides up in the slot p, thereby again throwing the unbalanced stress of the spring S upon the lever P to impart to the clutch an upward or separating movement. An important feature of this mechanism is that by reason of the relatively unyielding member T constituting a movable stop the spring S is enabled to be put under a considerable initial tension against this stop, so that when the armature movement occurs, by which the stop is displaced, the full tension of the spring is at once exerted to strongly and firmly press in the direction to draw the arc. This results in a uniform arc drawing or separating movement free from any fluctuation or dancing, and consequently without flickering or flashing of the light.

It is practically advantageous to introduce a yielding member between the lever P and clutch H, which is conveniently done by interposing a spring Q' as a part of the link Q.

It is preferable to provide a cushion g, Fig. 2, to receive the impact of the armature when it falls. This cushion is shown as placed in a recess in the bottom plate e' of the mechanism-frame B. It is also preferable to pro-

vide a buffer of felt or other material to receive the upward impact or shock of the armature when attracted.

In a lamp of the type shown an important desideratum is to make the entire lamp as short vertically as possible. My invention provides an improved arrangement of the regulating mechanism which contributes greatly to this end. By placing the intermediate lever P above the armature-lever F the armature when retracted may be brought directly down upon the bottom plate without shortening the spring S and without exposing the spring Q' beneath the mechanism-case.

An important feature of my invention relates to the means for adjusting the lamp for greater or less current. This I accomplish without affecting the initial stress of the spring S by varying the leverage or mechanical advantage with which it acts upon the clutch and reacts upon the armature. To this end, since the spring is connected in tension between the short arm of the lever F and the short arm of the lever P, I provide means for varying its leverage by varying the distance from the pivot or fulcrum at which it engages one or other of these levers. I prefer to provide the adjustment at its engagement with the lever P, as shown. As a convenient means for effecting this variation of leverage without requiring the dismounting of the spring, I have designed a screw adjustment by which the point of connection of the spring with the lever is readily moved toward or from the fulcrum-axis. Accordingly I provide a part movable along the short arm of the lever, which part is engaged by the spring, and I provide a screw adjustment for displacing this part toward or from the fulcrum-axis. In its most convenient and compact form this feature of my invention is constructed in the manner best shown in Fig. 16, where the upper end of the spring is looped around a nut h, so as to engage a circumferential groove therein, this nut screwing upon a screw-threaded pin or arm i, projecting from the lever and forming part of the short arm thereof. By turning the nut so as to screw it toward the lever-fulcrum the point of application of the spring is displaced toward such fulcrum, as shown in dotted lines in Fig. 16. To adjust the lamp for a greater current, the nut is screwed toward the right to shorten the effective length of the short arm of the lever. For a less current it is screwed outwardly to increase the effective length of the short arm of the lever. Of course if this adjustment were applied instead to the lever F the adjustments would be made in the contrary directions. This mode of adjustment accomplishes its result by merely changing the leverage at which the spring acts and without altering the length of the spring or affecting its initial stress.

In so-called "carbon-feed" lamps, wherein vertical compactness is attained by shortening the ordinary feed-rod into a mere plun-

ger, called the "trolley," sliding within a fixed tube, called the "trolley-tube," and causing the feed-clutch to engage directly with the upper carbon, which slides up within 5 the trolley-tube, difficulty is commonly experienced in conducting the current between the trolley-tube and trolley, since the slightest imperfection of contact is liable to result in the formation of small arcs which burn 10 the conducting springs or brushes and pit the inner face of the tube. Only a very light rubbing contact can be made between the trolley springs or brushes and the tube, as otherwise such friction would be generated 15 as would impair the free feeding down of the carbon. To overcome the disadvantages heretofore experienced, I provide a construction of trolley-brushes whereby these brushes or springs make edge contact with the tubular guide, the edges of the springs being presented against the inner face of the tube at so many points as to insure the making of a conductive connection such as shall avoid arcing or pitting. The trolley N is shown 20 within the tube in Fig. 11 and separately in Figs. 12 and 13. It is formed of a cylindrical plunger of suitable weight, having a suitable number of longitudinal grooves, in which are placed the contact springs or brushes *j j*, 25 which at one end are fastened to the trolley by screws or otherwise, and at their other or free ends press outwardly against the inner wall of the tube. The free ends of these springs are bent so as to present their edges outwardly 30 to bear against the tube. Preferably they are bent into U shape, as shown in Fig. 15, so that each spring presents both edges of said U-shaped portion to make edge contact with the inner surface of the tube. I prefer to 35 use three springs, so that six edges are presented in contact with the tube. Thus very light springs may be employed, pressing outwardly with very gentle pressure, and yet by reason of the numerous points of contact with 40 the tube they adapt themselves to all inequalities of surface and maintain ample conductive contact, thereby effectively preventing any arcing or burning, or the pitting or other injury of the tube. On the 45 bottom of the trolley is formed the carbon-holder L, consisting of a spring-clamp forming a yielding socket for receiving the upper end of the upper carbon I. The socket is preferably made integrally with the trolley, 50 as shown, the thin metal tube forming the socket being elastic and being cut or slotted by two or more longitudinal cuts *k*, which at their upper ends are carried around or continued by horizontal cuts *l*. This forms each 55 leaf of the socket of substantially L shape, so that it may yield either by expanding or contracting to fit slight variations in the diameter of the carbon, or may be distorted to adapt itself to a slightly-crooked carbon. 60 The upper end of the trolley and the upper end of the tube D are provided with reciprocal means whereby to center the trolley as

it is pressed up. These means consist of a projection on one part and a socket in the other, one or preferably both being conical. 70 I prefer to form a cone *n*, Fig. 11, upon a plug *o*, which closes the upper end of the tube D, and to form a socket *n'* in the upper end of the trolley. In trimming the lamp it is only necessary after removing the consumed carbon to push the new carbon up into the tube D, thereby sliding up the trolley until the latter strikes the stop-plug *o* and centers thereupon, and by the same movement seating the upper end of the carbon in the spring 75 clamp or holder L. The trolley is formed with a slight flange *q*, making an easy fit with the tube, and the tube has screwed on its lower end a collar *q'*, Fig. 11, the internal flange of which projects sufficiently far to arrest the flange *q* and prevent the trolley dropping out of the tube when removing the consumed carbon. The clutch H being arranged beneath the mechanism-case and engaging the carbon where it is liable to be considerably heated is subject to injury through wear and heating of its surfaces engaging the carbon. To prolong the life of the clutch, I construct it with a lining ring or bushing H', (shown best in Figs. 5 and 6,) which is held 80 in place by a small set-screw *r*, the end of which enters a circumferential groove in the bushing. When a bushing wears, it can, by loosening the screw, be turned around circumferentially to present new engaging surfaces or by partly withdrawing the screw it can be slipped out and inverted, thereby at 85 least doubling the life of the clutch. 90

The lamp shown is a long-burning or inclosed arc-lamp, the inner or smaller globe U 105 of which is held in a globe-holder V of improved construction. Heretofore much trouble has been experienced in providing a suitable construction of holder for this inner globe, many complicated devices having been 110 provided for this purpose. It is desirable that the base of the globe be held elastically, as any rigid holding means is liable to break it. It should also be constructed so as to be quickly and easily operated and should be 115 as simple and cheap as possible and not liable to get out of order. My improved construction aims to fulfil these conditions. I preferably construct the globe-holder integrally with the fixed part of the lower-carbon holder 120 K; but this is not essential. It is sufficient to provide any suitable globe seat, base, or socket *u*, Figs. 8 and 9, fastened in any suitable way to the bottom portion of the pendant frame—as, for example, in the manner 125 shown in Fig. 1, where it is fastened by screws to the yoke E', uniting the lower ends of the rods E E. The globe seat or base *u* preferably has a flange for supporting the foot of the globe, a packing *u'* being arranged 130 to cushion the globe, as shown, though this is not essential. It is also desirable but not essential that a flange *u''* should be provided to inclose the foot of the globe, forming a sort

of cup; but this is also unessential. That which is essential is that the foot or neck of the globe shall be engaged at substantially equidistant points by three (more or less) 5 studs, pins, or clamps *v v*, mounted on springs, so that they shall be pressed yieldingly toward the globe, so as to hold it elastically at preferably three points. I prefer to provide leaf-springs *w w*, one of which is shown separately in Fig. 10, which are extended peripherally around the globe-seat, being fixed at one end to the base *u* and carrying at their other ends the studs or clamps *v*. It is also desirable to provide a means for adjusting 10 the tension of these springs, and this I preferably attain by constructing the studs or clamps *v* as screws, the threads of which engage threaded holes in the free ends of the springs. Other means of adjustment may, 15 however, be provided. The screw studs or clamps are screwed outwardly to admit of placing the foot of the globe in the holder, whereupon they are screwed up to embrace the neck of the globe between them with a 20 suitable pressure. They cannot be made to press tighter against the glass than the tension of the springs, and hence the breakage of the globe by screwing up the screws too tightly is avoided, the springs being made of 25 proper stiffness to this end. The ends of the screw-studs are slightly upset, so that they cannot be lost out. The upper end of the globe *U* is closed, as usual, by a gas-cap *W*, which to allow for the expansion and contraction of the gases in the globe is provided 30 with a circuitous gas-passage *y*, as usual, one end of which, *y'*, Fig. 4, opens within the globe, while the other end *y''*, Fig. 2, opens externally. This passage *y* is formed, as heretofore, by 35 means of a groove in the upper side of the plate *W*, which groove is closed by fastening a flat plate *W'* on the top of the cast plate *W*. This top plate has heretofore been fastened down by screws; but this is objectionable, since 40 these screws interfere with the circuitous passage and occupy room otherwise needed therefor. My invention improves upon this construction by forming the plate *W* with a socket *x* in its upper side, as shown in Fig. 4, of a 45 diameter exactly equal to or, in fact, very slightly less than that of the plate *W'* in forcing this plate down into the socket under heavy pressure. This makes a permanent 50 union between the top plate and the casting 55 and avoids the disadvantage of fastening-screws.

In Fig. 1, *X* is the reactive coil employed in constant-potential alternating-current lamps.

I have shown in Figs. 1 and 2 an air-chamber *Y* beneath the mechanism-case in order to protect the mechanism-case and its contents from the heat of the arc, which in lamps of this class is apt to be a serious consideration, whereby because of the compactness of the arrangement the arc is brought close beneath the mechanism-case. The outer case surrounding this chamber *Y* is perforated

and communicates with an open hood, so that air can freely circulate on either side through the chamber *Y* to keep the parts cool. 70

My invention is by no means limited to the details of construction which I have herein-before set forth, but may be modified in many structural respects without departing from its essential features. These features I have 75 endeavored to set forth in the claims forming part of this specification. The unyielding member, of which the link *T* is an example, need not be absolutely unyielding, but should be substantially unyielding relatively to the 80 yielding member or spring *S*.

I claim as my invention the following-defined novel features, substantially as herein-before specified, namely:

1. The combination of a magnet, its armature or movable member, a separating device for drawing the arc, a retarder for restraining the separating action thereof, and means for connecting said armature and separating device, comprising a yielding member and a 85 relatively unyielding member, the former adapted upon the attraction of said armature to transmit a stress to said device tending to move it in the separating direction, and the latter adapted upon the retraction of said 90 armature to transmit a movement to said device in the contrary direction.

2. The combination of a control-magnet, its armature or movable member, a feeding device for separating and feeding the carbons, 100 a retarder for restraining the separating action of said feeding device, and means for connecting said armature and feeding device comprising a yielding member and a relatively unyielding member, the former adapted 105 upon the attraction of said armature to transmit a separating stress to said feeding device, and the latter adapted upon the retraction of said armature to transmit a feeding movement to said feeding device. 110

3. The combination of a magnet, its armature or movable member, a separating device for drawing the arc, a retarder for restraining the separating action thereof, and means for connecting said armature and separating device, comprising a yielding member and a 115 movable stop, the former under an initial stress, and the latter arranged to receive the reaction of said stress, the former adapted to transmit a stress upon the attraction of the 120 armature, and the latter to transmit a movement in the opposite direction upon the retraction of the armature.

4. The combination of a control-magnet, its armature or movable member, a feeding 125 device for separating and feeding the carbons, a retarder for restraining the separating action of said feeding device, and means for connecting said armature and feeding device comprising a yielding member and a 130 movable stop, the former under an initial stress, and the latter arranged to receive the reaction of said stress, the former adapted upon the attraction of said armature to trans-

mit to said feeding device a separating stress in excess of its initial stress, and the latter adapted upon the retraction of said armature to transmit a feeding movement to said feeding device.

5. The combination of a control-magnet, its armature, an armature-lever, a feeding device for the carbon, a retarder for restraining the separating action thereof, a lever intermediate of said armature-lever and feeding device, and means for connecting said levers comprising a spring and a movable stop, the latter serving to resist the stress of the spring, whereby the spring may be put under an initial tension, the spring arranged upon the attraction of the armature to transmit its stress to said intermediate lever to impart a separating movement, and the movable stop adapted upon the retraction of the armature 20 to impart a feeding movement.

6. The combination of a magnet, an armature-lever, a feeding device, an intermediate lever connected to said feeding device, and means for connecting said armature-lever and intermediate lever comprising a spring connecting said levers on one side of their fulcrums, and a relatively unyielding member connecting them on the opposite side of their fulcrums, said latter member having an engagement in one direction only so as to constitute a movable stop acting in opposition to said spring.

7. The combination of a magnet, its armature, an armature-lever F, a lever P, a link 35 T pivoted to one of said levers and engaging a slot in the other, a spring S connecting said levers in opposite position to said link, and a feeding device connected to said lever P.

8. The combination of a magnet, an armature-lever engaging the armature thereof beneath said magnet, a feeding device beneath said armature-lever, an intermediate lever above said armature-lever connected to said feeding device on the one hand and to said 45 armature-lever on the other, the latter connection comprising a spring and a movable stop, the latter serving to resist the stress of the spring, whereby the spring may be put under an initial tension, and a dash-pot connected to said feeding device.

9. The combination of a magnet, its armature-lever, a feeding device, an intermediate lever connected to said feeding device, a connection between said intermediate lever and armature-lever, and means for adjusting the 55 point of attachment of said connection to one of said levers so as to vary the leverage.

10. The combination of a magnet, its armature-lever, a feeding device, an intermediate lever connected to said feeding device, and a connection between said intermediate lever and armature-lever comprising a spring, and means for adjusting the leverage of said 60 spring by displacing its point of connection with one of said levers toward or from the fulcrum of such lever.

11. In an arc-lamp, the combination of a

magnet, its armature-lever, a feeding device, an intermediate lever, and a connection between said levers comprising a spring, and means for varying the leverage at which said 70 spring acts consisting of an adjusting device for moving the point of attachment of said spring with the lever toward or from the fulcrum of the lever.

12. In an arc-lamp, the combination of a magnet, its armature-lever, a feeding device, an intermediate lever, and a connection between said levers comprising a spring, and means for varying the leverage at which said 80 spring acts by varying its point of connection to the lever in direction toward or from the fulcrum thereof, and substantially perpendicular to the direction of stress of the spring, whereby the initial stress of the spring is not 85 varied by such adjustment.

13. In an arc-lamp, the combination with a lever P having a screw-threaded arm i, of an adjusting-nut h screwing on said arm, and a spring S engaging said nut.

14. In an arc-lamp, the combination with a lever P and a spring S acting against said lever, of means for varying the leverage at which said spring acts, consisting of an adjusting-screw engaging said lever and adjustable thereon in direction toward or from its fulcrum, said screw having a circumferential groove, and said spring having a loop entering said groove.

15. The combination of a feeding-clutch 100 and a removable bushing attached thereto having an inner gripping edge for engaging the movable electrode, and formed externally with a flange of greater width seated in the clutch.

16. The combination of a feeding-clutch having a circular recess, and an adjustable annular gripping edge seated therein for engagement with the movable electrode.

17. The combination of a feeding-clutch 110 and a bushing therefor movable within said clutch to different positions.

18. The combination of a feeding-clutch having a set-screw r, with a removable bushing H' having a circumferential groove adapted to be engaged by said screw.

19. In an arc-lamp, the combination with a trolley for engaging the carbon and its guiding-tube, of brushes for conducting the current between said trolley and tube attached to one part and arranged to press edgewise and to slide frictionally against the other.

20. In an arc-lamp, the combination with a trolley for engaging the carbon and its guiding-tube, of brushes for conducting the current between said trolley and tube consisting of metal springs attached to said trolley and bearing at their free ends against said tube, and bent to present at their free ends an edge contact with said tube.

21. In an arc-lamp, the combination with a trolley for engaging the carbon and its guiding-tube, of brushes for conducting the current between said trolley and tube consisting

- of metal springs attached to said trolley and bearing at their free ends against said tube, their free ends being bent into channel form to present both edges thereof in contact with 5 said tube.
22. In an arc-lamp, the combination with a trolley for engaging the carbon and its guiding-tube, said trolley formed with longitudinal grooves, and conducting-brushes consisting of springs fastened in said grooves at one end and bearing outwardly against said tube at their other ends, and bent to make edge contact with said tube at their free ends. 10
23. In an arc-lamp, a trolley for engaging the carbon having three longitudinal grooves, and conducting-brushes in said grooves consisting of springs fastened at one end and pressing outwardly at their opposite or free ends, and bent at said free ends to present 15 edge contact with the guiding-tube in which said trolley moves.
24. In an arc-lamp, the combination with a trolley for engaging the carbon and the guiding-tube of said trolley, the upper end of said 20 tube and the upper end of said trolley being provided reciprocally with centering means adapted to center said trolley when pressed up within said tube.
25. In an arc-lamp, the combination with a trolley for engaging the carbon and the guiding-tube of said trolley, the upper end of said trolley being provided with a conical recess, and the upper end of said tube being closed by a plug having a conical projection for engaging 30 said recess and centering the trolley.
26. In an arc-lamp, a trolley for engaging the carbon having a carbon-holder consisting of a socket divided into segments by longitudinal and transverse slits, whereby said 40 segments are adapted to yield in either direction.
27. In an arc-lamp, a trolley for engaging the carbon, the carbon-holder L consisting of a socket divided into segments by vertical slits 45 k and horizontal slits l, to the effect set forth.
28. In an arc-lamp, a globe-holder consisting of a plurality of studs adapted to engage the neck of the globe, and springs engaging 50 said studs and arranged to press them inwardly.
29. In an arc-lamp, a globe-holder consisting of a plurality of studs adapted to engage the neck of the globe, springs arranged to press them inwardly, and means for adjusting the tension of said springs. 55
30. In an arc-lamp, a globe-holder consisting of a plurality of studs adapted to engage the neck of the globe, each stud movable independently of the others, and springs engaging the respective studs pressing them independently toward the center. 60
31. In an arc-lamp, a globe-holder consisting of a plurality of screw-threaded studs adapted to engage the neck of the globe, and leaf-springs for pressing said studs inwardly 65 each spring fixed at one end and having at its other a screw-threaded engagement with its stud, whereby the studs may be independently adjusted in their respective springs to vary their tension. 70
32. In an arc-lamp, a globe-holder comprising a flanged base u, leaf-springs w w each fixed at one end to said base, and studs v v carried on the free ends of said springs, pressed inwardly thereby projecting inwardly 75 through the flange of said base, and adapted to engage the neck of the globe.
33. A globe-holder for an arc-lamp, comprising a globe-seat, a spring extending peripherally with relation thereto, and an adjustable clamp on the free end of the spring. 80
34. A globe-holder for an arc-lamp, comprising a globe-seat, a plurality of peripherally-extending springs mounted thereon, fixed at one end, and having adjustable clamps on 85 their free ends.
35. In an inclosed-arc lamp, a gas-cap consisting of a plate W grooved on its upper side to form a circuitous vent-passage, combined with a top plate W' for closing said passage, 90 the one plate being formed with a flange and the other fitting tightly within said flange and united thereto by being forced thereinto.
- In witness whereof I have hereunto signed my name in the presence of two subscribing 95 witnesses.
- JAMES J. WOOD.
- Witnesses:
- EDWARD A. BARNES,
FRED S. HUNTING.
